ATTORNEYS

UNITED STATES PATENT OFFICE.

EMIL STUMPF, OF ELBERFELD, GERMANY.

DESIGN FOR A FABRIC.

SPECIFICATION forming part of Design No. 21,342, dated February 16, 1892.

Application filed January 16, 1892. Serial No. 418,329. Term of patent 3½ years.

To all whom it may concern:

Be it known that I, EMIL STUMPF, a subject of the Emperor of Germany, residing at Elberfeld, Germany, have invented and produced a new and original Design for a Fabric, of which the following is a specification, reference being had to the accompanying drawing, forming a part thereof, which represents a plan view of a piece of fabric decorated in accordance with my design.

The leading feature of the design consists of the central ornament A, the bordering and adjacent ornaments B being "repeats" of the same. In detail the ornament A is a fanciful floral piece, the upper portion comprising a composite flower partly unfolded and sur-

rounded by leaves in marked contrast, the main flower being capped by smaller flowers of an essentially star-like design. The lower portion of the ornament is composed of overlapping stems and foliage, and at each side, apparently emanating from the main stem, composite flower figures smaller than the main flowers are arranged.

I claim—

A design for a fabric, substantially as herein shown and described.

EMIL STUMPF.
